UNITED STATES PATENT OFFICE.

CHARLES M. JEWELL, OF TULARE, CALIFORNIA.

LOOSE-LEAF LEDGER.

Application filed August 16, 1920. Serial No. 403,693.

To all whom it may concern:

Be it known that I, CHARLES M. JEWELL, a citizen of the United States, residing in Tulare, county of Tulare, State of California, have invented new and useful Improvements in Loose-Leaf Ledgers, of which the following is a specification.

This invention relates to loose leaf books in general, and the invention is particularly applicable to loose leaf books which are used as ledgers or the like, although the invention is not necessarily limited or restricted to such use, as will hereinafter appear. It is a general object of the invention to provide a construction and arrangement which shall be easily manipulated; in which the various sheets may be easily placed in, and if desired removed from the books; and an arrangement in which the various sheets are easily and immediately accessible for inspection or for entering of items. It is also a general object to provide a construction and arrangement wherein current monthly accounts, and previous monthly accounts, may be easily kept for ready inspection, and comparison, and making of entries.

Other objects of the invention, and the features of my invention, in a general and broad sense, as well as in its more specific sense, will be best understood from the following detailed description of a preferred form of the invention; reference for this purpose being had to the accompanying drawings in which—

Fig. 1 is a face view of my loose leaf book with the leaves opened out as in use; Fig. 2 is an end view of the book when closed; Fig. 3 is a fragmentary plan of the binding end of the book; Fig. 4 is a section illustrating how the individual current month entry sheets fit upon the binding posts of the book; Fig. 5 is a plan view showing one of the current month sheets, and Fig. 6 is an enlarged detail showing the configuration of the binding post and of the aperture in the sheet which cooperates with the binding post.

In the drawings I illustrate a form of book which includes a back-board 10 and front board 11. On the back-board there is mounted a suitable number of binding posts 12, and the front board 11 is provided with a thin metal plate 13, having holes 14 therein adapted to slide upon the binding posts 12, and two of the binding posts may

have cap screws 15 to prevent the front board 11 being moved entirely off the binding posts. The holes 14 in plate 13 of the front board 11 may be slightly larger than the binding posts, so as to allow the front board to move freely on the binding posts, and so also to allow the front board to have if desired, a little freedom of angular movement relative to the posts, to facilitate the opening out of the book. The back and front boards 10 and 11 may be made of any suitable material, and may be made in any suitable manner and with proper flexible joints, if so desired, so as to facilitate the opening out of the book. Thus, for instance, the front board 11 may have at 11^a a flexible part which facilitates the opening of the book. The cross sectional configurations of posts 12 are such, as hereinafter explained, as to facilitate easy sliding movement not only of the front board but also of the loose leaf sheets, upon the posts.

In the make-up of my book, particularly for use as a ledger, I place in the book, in corresponding sets, as is best illustrated in Fig. 1, a sheet 20 and a plurality of current month entry sheets 21 in such an arrangement that when the book is opened out as shown in Fig. 1 the current month entry sheets 21 will then appear approximately opposite the general entry sheet 20. The general entry sheet 20 is ruled to contain the names of several customers and is ruled to contain monthly balances. For instance it may be ruled to contain monthly balances for the past six months; and it will be well understood how another sheet may be arranged in the same way to contain the monthly balances for the other six months of the year, and how the individual current month entry sheets may be placed in the book opposite the appropriate sheet 20, as desired. These current month entry sheets 21 are of relatively small extent—they are not as high as the sheet 20; and they are placed upon posts 12 in an overlapping or overlying relation, as is best illustrated in Figs. 1 and 4. The distance between posts 12 and the number of posts, the width of the sheet 21, and the disposition of the post engaging apertures in sheets 21, are all so relatively arranged that each sheet 21 will preferably engage with and be held by at least two of the posts. A great number of sheets 21 may be placed upon the posts; and the entry sheet 20 may carry a correspondingly large

number of names. The arrangement is such that the top of the individual sheet 21 with its customer's name thereon, comes about opposite the entry of the customer's name on 5 the top on sheet 20; so that the two series of entries on the two sheets are readily referable, one to the other. Sheet 20 carries a statement of the past months' balances, together with whatever notations are desirable, such as date of payment, etc., while the sheet 21 carries the daily entries for the account of the current month. When the current month is finished, then the balance from sheet 21 is placed on sheet 20 and sheets 10 15 21 are taken out of the books and fresh sheets are put in.

Now the sheets 21 are in reality double sheets, as is best shown in Fig. 4. Each sheet 21 has a front leaf 21^a and a back leaf 21^b; and the upper edge 21^c of the back leaf projects upwardly beyond the upper edge of the front leaf 21^a. A carbon paper is inserted between the two leaves of the sheet, so that the entries made on the front leaf will be duplicated on the back leaf. 25 The projection at 21^c insures that the carbon paper may be readily placed between the two leaves of the sheet without any danger of the carbon paper being placed beneath 30 the lower leaf 21^b.

Thus, when a sheet 21 is removed from the book, there are in it two copies of the current monthly account. These two copies may then be separated along the fold 21^d at 35 the bottom of the sheet, and the two copies filed or used as desired, and according to the system of records pursued. For instance, one may be mailed to the customer and the other filed for reference.

40 The cross sectional configuration of posts 12, and the corresponding configuration of the openings in various sheets, is of importance, as it allows ready and easy insertion of the sheets, and also allows the sheets to 45 slide easily on the posts so that the book may be opened up as indicated in Fig. 1. Each post has a cross sectional configuration such as illustrated in Fig. 3 and as shown in enlarged detail in Fig. 6. The two opposite sides of the post at 12^a converge toward 50 the inner side of the post to a relatively narrow inner surface 12^b. It is preferred not to have the two surfaces 12^a converge completely to a sharp edge at the inner side 55 of the post in order to prevent the sheets from being cut or split at that point, and to provide certain other advantages hereinafter explained. At the outer side of the post there are two outwardly converging 60 surfaces 12^c which meet a broader outer surface 12^d, which outer surface 12^d is substantially parallel to the inner surface 12^b. It will be seen that the sectional configuration of the post may be substantially de- 65 scribed as being made up of two trapezoids

placed with their bases together (their bases being a line extending between the intersection points of surfaces 12^a and 12^c). Now the aperture 30 in the sheet is made of substantially the same configuration as the 70 cross section of the post, the aperture being made slightly larger than the post so as to fit easily around the post; and leading from the aperture to the outer edge 20^a of the sheet there is an opening 20^b wider at the 75 outer edge of the sheet than where it communicates with the opening 30. Where this opening 20^b communicates with opening 30 there are left two edges 30^d which engage with the outer flat surface 12^d of the post; 80 and it is these two corner edges 30^d, together with the diagonal edges 30^e, that prevent the sheets from becoming accidentally disengaged from the post. These parts prevent the sheets from being disengaged from 85 the post, even if the book is held up vertically and shaken violently; yet at the same time the sheets may, if desired, be removed from the post. The action then is that the diagonal edge surfaces 30^e engage 90 with the diagonal surfaces 12^e of the post and spread that part of the sheet apart and cause displacement of those parts of the sheet adjacent edges 30^d and 30^e from a true plane. This action may be somewhat fa- 95 cilitated by twisting the sheet by hand out of true flatness at the same time it is pulled outwardly. To insert the sheet it is only necessary to slide it inwardly onto the post. The width of the aperture 20^b at the outer 100 edge of the sheet is wider than the surface 12^c at the inner side of the post; so that the two tapering edges of the opening 20^b will be put into engagement with the tapering surfaces 12^a of the post. Inward move- 105 ment then of course expands the aperture 20^b by forcing apart its converging side edges until the edges 30^d have passed the widest part of the post. Then these edges 30^d and 110 the edges 30^e move easily into engagement 110 with the corresponding parts of the post. In this action the parts along the converging edges of opening 20^b are of course displaced (bent) from the normal plane of the sheet; but due to the obtuse angle at 20^e there is no 115 tendency to turn a "dog-ear" at that corner as there is in most loose leaf sheets which have a slot leading from the post aperture to the edge of the sheet.

It will thus be seen that my construction 120 provides a very simple and effective means of releasably holding the sheet on the post; the sheets may be removed from the post, and are very easily inserted. This ease of insertion adds very greatly to the effectiveness of my system; as the current month entry sheets may be removed and replaced by others and may be very easily moved from place to place in the book, and as the entry sheets 20 may be removed and re- 125 130

placed, or changed from place to place in the book, without any trouble. Ordinarily the sheets are only removed at the end of a month; when all sheets 21 are changed; and 5 this is done by taking off the top board and lifting the sheets off the posts. But any of the sheets may be very easily inserted without taking the book apart.

In order to facilitate putting a large number of sheets 12 in overlapping relation, these sheets may have a plurality of apertures 30; say two pairs of apertures, and either pair may be engaged with any two posts. Now, while I prefer to engage each 15 sheet with at least two posts, my design is of such accuracy that a sheet may even be held by one post. This accuracy of holding the sheets in alinement is due to the two opposite flat post surfaces 12^b and 12^d which 20 the corresponding sheet edges 30^b and 30^d fit fairly snugly, preventing any substantial displacement of the sheet. And the breadth of these flat surfaces reduces wear on the 25 sheets and thus minimizes any tendency of the sheets to wear loose. Furthermore, these broad surfaces make the sheets slide easily on the posts without binding.

Having described a preferred form of my invention, I claim:

30 1. In a device of the character described, the combination of a suitable back-board and a plurality of sheet-holding posts in spaced relation thereon, a general entry sheet used for and adapted to receive 35 monthly balances of a number of customers, and a plurality of current month entry sheets, smaller in size than the general entry sheets and adapted each to receive a current monthly account of an individual customer; 40 such current month entry sheets being mounted upon said posts in overlapping relation to each other and each of said sheets engaging at least two of said posts; each

current monthly entry sheet being composed of two leaves, one superimposed upon the 45 other, and the lower leaf having its upper edge projecting beyond the upper edge of the upper leaf.

2. In a loose leaf book, the combination of a binding post whose cross section is substantially two trapezoids placed face to face, and a sheet having an aperture therein spaced from its edge and an opening leading from its edge to the aperture, said opening being wider at the edge of the sheet 55 than where it communicates with the aperture, and said aperture being substantially similar in form to the cross section of the post.

3. In a loose leaf book, the combination 60 of a binding post whose cross section is substantially two trapezoids placed face to face, and a sheet having an aperture therein spaced from its edge, and an opening leading from its edge to the aperture, said opening being wider at the edge of the edge of the sheet than where it communicates with the aperture, and said aperture being substantially similar in form to the cross section 65 of the post; the outer and inner faces of the post being substantially parallel, and the outer face being wider than the inner face; and the width of said opening at the outer edge of the sheet being wider than the width of the inner face of the post, and the 70 width of said opening where it communicates with the aperture in the sheet being narrower than the width of the outer face of the post.

In witness that I claim the foregoing I 80 have hereunto subscribed my name this 7th day of August 1920.

CHARLES M. JEWELL.

Witness:

GLENN L. MORAN.
